COMPARTMENTAL WASHING MACHINE

Walter A. Frantz, Cleveland Heights, Ohio, assignor to The Apex Electrical Manufacturing Company, Cleveland, Ohio, a corporation of Ohio

Application April 14, 1930, Serial No. 444,110
Renewed September 29, 1933

24 Claims. (Cl. 68—27)

This invention relates to washing machines generally and in particular to washing machines adapted to provide a plurality of separate washing compartments which may be used selectively or simultaneously at the will of the operator.

Prior to my invention some of the more expensive washing machines provided means for regulating the speed and in some cases the stroke of the machine in order to efficiently and safely wash different kinds of articles, that is, for rough and heavy work the machine would be run at a relatively high speed providing a strong agitation of the detergent fluid in the tub. For the washing of fine silks and other fragile articles a less violent degree of agitation is desired in order to prevent tearing and undue wear on such articles when subject to the washing operation and when washing such articles the machine would be run at a slow speed or short stroke.

Washing machines of the type just described while providing a flexible machine capable of accomplishing the desired results are objectionable in that they are relatively expensive and complicated, restricting their use and sale to the high price field of purchasers.

It is the object of this invention to combine in a single inexpensive washing machine a plurality of washing compartments adapted to be operated by a common means whereby the fluid in the individual compartments of the machine is agitated at different degrees of intensity and whereby at one and the same time different articles requiring different washing treatment may be washed at the same time and whereby the different compartments may be used singly or together at the will of the operator and whereby separate and distinct detergent solutions may be carried in individual compartments of the machine for the separate washing of different classes of articles.

A further object of this invention relates to certain improvements in method and apparatus for the washing of clothes whereby the clothes are subjected to individual washing action as distinguished from collective action, the same being accomplished with the machine disclosed by configuring the agitator so that during the agitation of the tub contents the fluid and clothes are circulated continuously in one direction about the tub axis with the result that the articles being washed are successively and progressively presented to the zones of activity of the impelling surfaces of the agitator and thus are separated, unfurled, flexed and acted upon piece by piece and part by part during the washing operation.

Stated in general terms, my invention consists in replacing the usual agitator member of a washing machine with a hollow agitator, the interior of which is adapted to provide a separate washing compartment and in which a different or the same detergent solution as carried in the tub may be used, the exterior of the agitator cooperating with the tub in the ordinary manner for the agitation of the contents thereof.

The washing action within the agitator is less violent than the action in the tub and the interior of the agitator is particularly adapted for the washing of small and fragile articles such as handkerchiefs, lace curtains, silk stockings, etc., while the space between the agitator and the tub may be used for the washing of heavier and coarser articles requiring a more violent action for their cleaning.

With these and other objects and advantages in view, the invention consists of the novel construction arrangement and combination of parts hereinafter described and illustrated in some of its embodiments in the accompanying drawing and particularly pointed out in the appended claims.

Referring to the drawing, Fig. 1 is a side elevational view partly in section of a washing machine embodying my improved agitator. Fig. 2 is a plan elevational view of a modified form of agitator adapted to replace the agitator shown in Fig. 1. Fig. 3 is a side elevational view of the agitator shown in Fig. 2. Fig. 4 is a plan elevational view of another form of agitator adapted to replace the agitator shown in Figs. 1 and 2, and Fig. 5 is a side elevational view of the agitator shown in Fig. 4.

For the purpose of illustration I have shown my improved agitator in connection with a conventional gyrator type washing machine having a base 1 in which is housed a suitable motor (not shown) connected to gear mechanism within the case 3 by means of a belt 4. A tub 2 is supported on the base 1 of the machine above the gear case 3. A drive shaft having a splined head 6 projects through the bottom of the tub. This shaft is adapted to be driven by the motor through suitable gear mechanism in the case 3 with an alternating rotating movement as is customary.

The shaft and head 6 are adapted to detachably support and drive through the cooperating element 11 an agitating member 5 which in the present case comprises a cylindrical hollow member having baffled plates 7 located in the bottom thereof and vertically disposed baffle plates 8 located exteriorly thereof. A cover 9 having a

suitable catch or fastener 18 is provided to close the top of the agitator or container 5. With the parts in position as shown, the compartments defined by the interior of the agitator 5 and space between it and the tub 2 may be filled with a detergent fluid and the machine placed in operation.

The interior of the element 5 is adapted to be used for the washing of small and fragile articles 10 and the space between the agitator 5 and the tub 2 is adapted for the washing of heavier and less fragile articles. By reason of the construction shown agitation within the container 5 is relatively gentle as compared with the agitation 15 produced in the annular space defined by the tub 2 and the container 5.

Furthermore, it is to be noted that detergent fluids of different strength may be readily used in the different compartments so that it is possible 20 not only to control the degree of agitation in the different compartments, but the strength of the washing or detergent fluid as well.

By reason of this construction it is possible to do a complete washing comprising a variety of 25 articles with one filling of the tub and its container as the two different detergent solutions and two different washing actions are sufficient to take care of most any article to be washed.

The modified forms of agitator shown in Figs. 30 2 to 5 inclusive are provided with containers of irregular outline so that the side walls of the container take the place of the agitating members or baffles 7 and 8 of the device shown in Fig. 1.

Referring to Figs. 2 and 3 wherein is shown a 35 container having a base plate 14 supporting an irregularly shaped container with inner and outer notched edges 13 and 18 which are adapted to provide a means for the agitation of the liquid in the tub as well as that within the container 40 itself.

During the washing operation of this form of 45 agitator the notched walls of the container, due to their ratchet-like configuration, serve to move the clothes and liquid outside the container continuously in a clockwise direction while at the same time moving the clothes and liquid inside the container continuously in a counterclockwise direction. By reason of this mode of operation, 50 all of the articles being washed both inside and outside the container are subjected successively and repeatedly to the washing action of the notched edges 13 and 18.

In the modification shown in Figs. 4 and 5 a 55 plate 17 similar to the plate 14 of Fig. 2 is used. In this modification the contour of the container is slightly different the wall 15 being shaped to provide 4 blades 16 which function during the 60 operation of the device to agitate the liquid of the tub as well as the fluid contents of the container.

From the foregoing it will be apparent that I 65 have provided a single tub washing machine having a plurality of compartments adapted to provide for the washing of different kinds of articles at different degrees of agitation without the addition of extra parts to the essential elements of a washing machine of the type shown.

In the present invention, the washing action 70 of the machine is effected to a considerable extent through the vigorous circulation of the clothes and washing fluid, as distinguished from washing machines of the type in which the washing action consists primarily in rubbing and 75 scrubbing the clothes. In place of corrugated

rubbing and scrubbing surfaces of the type shown in Lockhart Patent No. 311,133, the agitating devices in the present invention exhibit liquid impelling surfaces of substantial size which are circumferentially spaced apart from each other 5 a substantial distance so as to act upon separate and distinct portions of the contents of the washing compartment and vigorously agitate the same during the operation of the machine.

The bottom of the inner container is located 10 closely adjacent to the bottom of the outer container or tub so as to prevent the articles being washed from working beneath the inner container and becoming tangled and torn, as would probably be the case if one were to attempt to use a 15 churn of the type shown in Truitt et al. Patent No. 1,737,265 for the washing of clothes.

If desired the complete washing operation may be done in the removable container 5 as where the articles to be washed are few in number or 20 are of such kind as to require the gentler action of this device. In such case it is not necessary to fill or empty the relatively large tub 2.

Due to the small size of the container 5 it may be readily removed from or replaced in the tub 25 5, further facilitating the washing operation and permitting at the same time the use of cleaning fluids such as gasoline and naphtha which would be dangerous to use in the open tub 2. When used for dry cleaning purposes the articles to be 30 cleaned and fluid are placed in the container in some safe place such as out of doors and the cover 9 securely fastened in place. The container 5 is then carried to and placed in the washing machine where it may be agitated for 35 the desired length of time and then bodily carried to a safe place for the removal of the cleansing fluid and articles that were cleaned.

The oscillatable containers illustrated herein 40 constitute in effect hollow agitators for the liquid contents of the tub included within the space between the walls of such agitators and the side walls of the vat or tub 2. In the form of the device illustrated in Figs. 2 to 5, the side walls of the containers are configured so as to constitute agitating or impelling members or blades of considerable thickness which act in much the same manner as the more usual form of blade 8 carried by the container 5.

In the operation of the device illustrated in 50 Figs. 2 and 3, when the container is moved counterclockwise, the liquid adjacent to the notches is given a spiral motion in a horizontal plane and thrown outwardly at the same time and when the device is rotated in a reverse direction, the 55 clothes are sucked inwardly behind the blade formed between the notches 13 and 18 with a reverse spiral motion to that just mentioned. During successive operations of the device, clothing and liquid move in a well-defined path about 60 the vat in one general circulatory direction with an intermittent retardation for each counterclockwise movement of the agitator and as the clothes are worked upon in this manner, they are separated, unfurled and flexed as they come into 65 the zone of action of the agitating surfaces of the device and in this manner a uniform and thorough washing action is secured which may be referred to as individual action on the clothes as distinguished from collective action in which 70 the clothes and liquid are acted upon as a body.

The agitating or liquid impelling surfaces provided in all devices illustrated herein, is effective for washing purposes from the top liquid level to the bottom of the vat or tub and in the device 75

shown in Figs. 2 and 3 they define channels extending downwardly from the top surface of the liquid toward the bottom of the vat.

While I have shown my improved washing device in connection with a gyrator type washer to which type of machine it is particularly adapted, it is apparent that such device could be readily adapted to other types of washing machines.

Furthermore it is to be understood that the particular forms of apparatus shown and described and the particular procedure set forth are presented for purposes of explanation and that various modifications of said apparatus and procedure can be made without departing from my invention as described in the appended claims.

Having thus described my invention what I claim is:

1. A clothes washing machine comprising a tub, operating mechanism including a vertically disposed oscillatable shaft projecting through the bottom of said tub, means for driving said mechanism, and a container having a socket in its bottom adapted to receive the upper end of said shaft in supporting and operating relation, the interior of said container constituting a small capacity washer, and the walls of said container being spaced from the wall of said tub to define an external larger capacity washer, and agitator elements both inside and outside said container and formed as a part of said container whereby the liquid contents of the respective washers are agitated upon the oscillation of said container by said shaft.

2. An oscillatable agitator for washing machines which is itself made hollow to constitute a second container having internal vanes for the agitation of the liquid contents thereof and having external vanes on the side walls thereof for agitating the liquid and fabric contents surrounding the same in the washing machine wherein it is used, said agitator having a socket for attachment to an operating shaft and the side wall of said agitator being imperforate.

3. A clothes washing machine comprising a tub, an agitator therein mounted for movement about a vertical axis, said agitator being formed with walls defining an open cell within the same and having liquid agitating provisions exteriorly thereof, agitating provisions inside the cell of said agitator, and means for actuating said agitator and with it said agitating provisions with a reversely rotary movement.

4. In a washing machine, a tub, a shaft in said tub, an agitator mounted on said shaft, operating means for imparting movement to said shaft and agitator, said agitator having a sinuous upstanding wall free of abrasive corners and providing a liquid chamber and agitating surfaces, and means closing said liquid chamber.

5. In a washing machine, a tub, a shaft in said tub, an oscillator including a sleeve disposed about said shaft and supporting said oscillator in said tub, said sleeve including an outwardly flared portion at the lower end thereof, a sinuous wall extending upwardly from said outwardly flared portion in spaced relation with said sleeve and providing a liquid chamber on said oscillator and liquid agitating surfaces, and operating means for imparting movement to said shaft and oscillator.

6. In a washing machine, a tub, a shaft in said tub, an oscillator including a sleeve disposed about said shaft and supporting said oscillator in said tub, said sleeve including an outwardly flared portion at the lower end thereof, a sinuous

wall extending upwardly from said outwardly flared portion in spaced relation with said sleeve and providing a liquid chamber on said oscillator and formed of alternate ribs and pockets extending substantially parallel with the wall of the tub and providing liquid agitating surfaces, and means for imparting movement to said shaft and oscillator.

7. In a washing machine, a tub adapted to receive liquid and a batch of clothes, an agitator in the tub mounted for movement about a vertical axis and having a chamber also adapted to receive liquid and a batch of clothes, the side wall of said chamber including means for agitating the contents of the tub and the contents of the chamber conjointly or selectively, dependent upon whether there is liquid in the chamber or the tub or both, and means for operating said agitator.

8. In a washing machine, a tub adapted to receive liquid and a batch of clothes, an agitator in the tub and including a bottom and a wall extending upward from said bottom and providing a cleansing chamber also adapted to receive liquid and a batch of clothes, said wall having exterior and interior protuberances to agitate the contents of the tub and the contents of the chamber conjointly or selectively, dependent upon whether there is liquid in the chamber or the tub or both, and means for operating said agitator.

9. In a washing machine, a tub adapted to receive liquid and a batch of clothes, an agitator mounted in the tub for movement about a vertical axis and having a chamber also adapted to receive liquid and a batch of clothes, said chamber having a sinuous side wall to agitate the contents of the tub and the contents of the chamber conjointly or selectively, dependent upon whether there is liquid in the chamber or the tub or both, and means for operating said agitator.

10. In a washing machine, a tub adapted to receive liquid and a batch of clothes, an agitator mounted in the tub for movement about a vertical axis and having a chamber also adapted to receive liquid and a batch of clothes, the side wall of said chamber including exterior and interior rounded corners and pockets to agitate the contents of the tub and the contents of the chamber conjointly or selectively, dependent upon whether there is liquid in the chamber or the tub or both, and means for operating said agitator.

11. In a washing machine, a tub adapted to receive liquid and a batch of clothes, an agitator in the tub and including a bottom and a sinuous wall extending upwardly from said bottom and providing a cleansing chamber also adapted to receive liquid and a batch of clothes, said sinuous wall being adapted to agitate the contents of the tub and the contents of the chamber conjointly or selectively, dependent upon whether there is liquid in the chamber or the tub or both, means for preventing the liquid from splashing out of the chamber, and means for operating said agitator.

12. In a washing machine, a tub, a shaft in said tub, an agitator mounted on said shaft, and operating means for imparting movement to said shaft and agitator, said agitator having a sinuous upstanding wall free of abrasive corners and providing a liquid chamber and agitating surfaces.

13. In a clothes washing machine, a tub, an element movably mounted on a vertical axis in said tub for dividing the same into different washing compartments, means for agitating liquid and articles to be washed in such compartment.

ments at relatively different intensities, and mechanism for operating said last-named means.

14. In a washing machine, a tub for detergent liquid and articles to be washed, a hollow agitator in said tube dividing the same into two different washing zones, one inside the agitator and the other surrounding the same, and means for oscillating said agitator about a vertical axis, said agitator having interior and exterior agitating provisions adapted for imparting different degrees of agitation to the liquid inside the agitator and the liquid surrounding the same.

15. In a washing machine, a tub for containing a detergent liquid and articles to be washed, a hollow agitator projecting upwardly from the bottom of said tub adapted for reception of detergent liquid and articles to be washed, and means for oscillating said agitator, said agitator having interior and exterior liquid agitating provisions whereby during the oscillation of said agitator a relatively high degree of agitation is imparted to the liquid outside the agitator and a relatively low degree of agitation is imparted to the liquid inside said agitator.

16. In a washing machine, a tub for containing detergent liquid and articles to be washed, a shaft projecting through the bottom of said tub, means for oscillating said shaft, and a container for clothes and liquid having a bottom with an upwardly projecting dome fixed therewith and defining a socket for the reception of the end of said shaft inside said tub, said container having liquid agitating provisions exteriorly and interiorly thereof and said shaft and socket having non-circular complementary sides whereby the shaft forms a detachable driving connection with said socket.

17. In a clothes washing machine, a tub for containing detergent liquid and articles to be washed, a hollow agitator extending upwardly from the bottom of said tub and itself adapted for the reception of detergent liquid and articles to be washed, and means for oscillating said agitator about a vertical axis, said agitator having interior and exterior liquid impelling surfaces adapted to agitate the liquid in the agitator and in the tub while at the same time continuously moving such liquid circularly about the axis of oscillation of said agitator.

18. In a clothes washing machine, a tub for containing detergent liquid and articles to be washed, a hollow agitator extending upwardly from the bottom of said tub and itself adapted for the reception of detergent liquid and articles to be washed, and means for oscillating said agitator about a vertical axis, said agitator having interior and exterior liquid impelling surfaces inclined with respect to the instantaneous direction of their movement so as to agitate the liquid in the agitator and in the tub while at the same time continuously moving the liquid inside and outside the agitator circularly about the axis of oscillation thereof and in different directions.

19. A single tub clothes washing machine comprising, an outer tub and associated means in the tub defining therewith a plurality of washing compartments located one inside the other and adapted for the simultaneous reception and agitation of detergent fluid and two different batches of clothing, shaft means operable about a vertical axis, agitating elements connected to said shaft means and located in the compartments

of said tub extending upwardly from a position closely adjacent to the bottom thereof so as to prevent the entry of clothing therebeneath for effecting the simultaneous agitation of the contents of said compartments, and operating means for said shaft means.

20. A clothes washing machine comprising, casing means defining a plurality of washing compartments located one inside the other and adapted for the simultaneous reception of different batches of clothing and different detergent fluids, means operable about a vertical axis including a shaft and agitating elements in the compartments of said casing means extending upwardly from a position closely adjacent to the bottom thereof so as to prevent the entry of clothing therebeneath for effecting the to-and-fro excitation of the contents of both said compartments, and mechanism for oscillating said shaft.

21. A clothes washing machine comprising casing means defining a plurality of washing compartments located one inside the other and adapted for the simultaneous reception of different batches of clothing and detergent fluid, washing means operable about a vertical axis comprising a shaft and agitating elements in the compartments of said casing means for effecting the to-and-fro excitation of the contents of said compartments at different intensities, and operating means for said shaft.

22. A washing machine comprising a tub adapted for the reception of a detergent liquid and fabric articles to be washed, operating mechanism outside said tub, substantially vertically disposed shaft means associated with said mechanism extending through a wall of said tub and driven by said mechanism, wall members spaced inwardly from the tub side walls defining a compartment inside said tub, and liquid impelling elements inside said compartment and in the space between said wall members and the side walls of said tub operably connected to said shaft means.

23. A single tub clothes washing machine comprising a tub having a plurality of washing compartments one inside the other and adapted for the simultaneous reception of articles of clothing and detergent fluid, washing means operable about a vertical axis comprising a single operating element located inside said tub and defining the inner compartment of said tub, said element having agitating surfaces in contact with and for simultaneously effecting the to-and-fro excitation of the contents of both said compartments, and operating means for said washing means.

24. A clothes washing machine having a plurality of washing compartments comprising a liquid holding tub, a clothes container of materially smaller size extending upwardly from the bottom of said tub whereby separate washing compartments are defined by the space within said container and by the space between the side walls of said container and the adjacent walls of said tub, the bottom of said container being located closely enough to the bottom of said tub so as to prevent the movement of clothes therebeneath, liquid agitating elements both inside said container and in the space between said tub and said container, and means for oscillating said agitating elements.

WALTER A. FRANTZ.
